UNITED STATES PATENT OFFICE

WILLIAM R. BARNHART, JR., OF WOOSTER, OHIO.

LOADING DEVICE.

1,321,781.

Specification of Letters Patent.

Patented Nov. 11, 1919.

Application filed July 14, 1919. Serial No. 310,631.

To all whom it may concern:

Be it known that I, WILLIAM RALPH BARNHART, Jr., a citizen of the United States, residing at Wooster, in the county 5 of Wayne, State of Ohio, have invented certain new and useful Improvements in Loading Devices, of which the following is a description, reference being had to the accompanying drawings, forming a part hereof.

10 My invention relates to loading devices for loading bricks and similar articles onto railway cars or other vehicles and has for its object to provide a device by which a load of bricks or similar articles piled or arranged in a definite order on a movable platform or yard car, may be transferred to the railway car or other vehicle without disturbing the pile or arrangement of the bricks or other articles and without injury to the 15 bricks or other articles, thus saving the expense of rehandling as well as the loss by breakage liable to result from rehandling. A further object of the invention is to provide a device for the purpose indicated 20 which may be readily shifted from one place to another without taking it apart.

25 With these and other objects hereinafter explained in view my invention consists in the construction and combination of elements hereinafter described and claimed.

Referring to the drawings;

Figure 1 is a side elevation, partly broken away, of a complete loading device embodying my invention.

35 Fig. 2 is a front elevation of the device shown in Fig. 1.

Fig. 3 is a view similar to Fig. 1 but showing the loading device resting on a vehicle ready to be moved to another place.

40 Fig. 4 is a detail side view of one of the rails carried by the suspended frames showing the joint between the portions of the rail.

45 Fig. 5 is a detail cross sectional view of the movable platform or yard car.

Fig. 6 is an end view of the inclined track support with the rail supporting brackets in position to permit the loading device to be moved.

50 Fig. 7 is a cross sectional view on line 7—7 of Fig. 6, and

Fig. 8 is a detail side view of the end support of the inclined track.

55 In the drawings 1 and 2 indicate the terminal portions of rails adapted to support

the wheels 3 of a movable platform or yard car 4. The terminal portion 1 is hinged or jointed at 5 to a horizontal portion 6 and the terminal portion 2 is hinged or jointed at a point in line with 5, to a horizontal portion similar to and parallel with 6, not necessary to be shown. The forward ends of the terminal portions 1 and 2 rest on the lower cross bar 7 of a suspended frame formed by the lower cross bar 7, uprights 8 and 9, and upper cross bar 10. Midway between the ends of the upper cross bar 10 is swiveled the lower end of a screw 11, this screw extending upward through a cross bar 13 which is supported by uprights 14 and 15, resting on suitable bases adapted to rest on the ground without being permanently secured thereto. The uprights 14 and 15 are suitably braced together to form a rigid structure. The screw 11 is provided at its upper end with a hand wheel 16 by which the screw may be rotated to raise or lower the frame formed by the cross bars 7 and 10 and the uprights 8 and 9, to raise or lower the forward ends of the terminal portions 1 and 2 of the rails.

A second suspended frame corresponding in construction to the suspended frame above described as formed by the cross bars 7 and 10 and the uprights 8 and 9, is located in line with the rear ends of the terminal portions 1 and 2, with its lower cross bar directly below the joint or hinge 5 and the joint or hinge at the rear end of the terminal portion 2. This second suspended frame is preferably provided with two elevating and lowering screws 20 and 21 extending through nuts 22 and 23 respectively, on a cross bar 24 carried by uprights corresponding to uprights 14 and 15. The cross bars 13 and 24 are connected together by longitudinal rods 25 so as to form a rigid supporting structure sufficiently strong to support the weight of the track and a loaded car. The horizontal portion 6 and the corresponding portion of the other rail are arranged to be supported at their rear ends in line with the rails of an inclined track 32 carried by a series of upright frames 26, 27, 28, 29, 30, 31, of gradually decreasing height 105 suitably braced together to form a rigid structure.

The rear ends of the horizontal portion 6 and the corresponding portion of the other rail are detachably supported in line with 110

the rails of the inclined track by any convenient means which, when out of supporting position, will permit the ends of these horizontal portions to move downward 5 freely to the position in which they are shown in Fig. 5. In the construction shown the uprights of the end frame 26 are each provided with a hinged bracket 50 resting, when in line with and supporting the ends 10 of these horizontal portions, on a cross bar 51 carried by the uprights and so constructed that when swung outward as shown in Fig. 6, they will be out of the way of the ends of these horizontal portions.

15 A pulley 33 is carried by the end frame 26 midway between the uprights which carry the brackets 50, in bearings 34 supported by the cross bar 51 and braces 52, and on this pulley is carried an endless cable 35 for moving the movable platform or yard car 4 up the inclined track onto the elevated rails carried by the suspended frames. These suspended frames hold the portions of the track carried by them, when the device is to 20 be used for loading, at an elevation sufficiently high to permit the vehicle to be loaded, here shown as a railway car 40, to be run under them and to allow some space for dumping.

30 The movable platform or yard car 4 is preferably formed of a pair of I beams 41 and 42 provided on their under sides with suitable bearings for the axles of the wheels 3 which are arranged on the outsides of the 35 I beams, and provided on their inner sides between their flanges with bearings for the ends of rollers 43. These rollers 43 are arranged close together so as to form a suitable support for the pile of bricks 45 off which 40 the bricks will slide or slip when the front end of the car is sufficiently depressed as hereinafter described. A suitable brace 47 at the rear end of the car serves to prevent the pile of bricks from sliding off the rear 45 end of the car as the car is drawn up the inclined track.

The elevating and lowering screws 11, 20 and 21 are of such length that when rotated to lower the suspended frames they will 50 bring the lower cross bars against the platform of the vehicle 40 and when further rotated, they will lift the cross bars 13 and 24 and with them the supporting uprights 14 and 15 and the uprights which support 55 the cross bar 24 so that the bases of these uprights will be clear of the ground and the complete loading device, except the inclined track, may be moved by the vehicle to any desired place.

60 In operation when the railway car or other vehicle 40 is in position below the suspended frames as shown in Fig. 1, a movable platform or yard car 4 previously loaded with bricks or other articles arranged 65 in a definite order or pile, is drawn up the

inclined track 32 by the endless cable 35, or by other means if preferred, the movable platform or yard car being connected to the cable, if the cable is used, at its rear end, and is pushed forward onto the portion of the 70 track which is carried by the suspended frames until about one-third of the length of the movable platform or yard car is forward of the forward suspended frame. The hand wheel is then operated to rotate screw 75 11 to lower the forward suspended frame thus lowering the front ends of the hinged terminal portions 1 and 2 and lowering with them the front end of the movable platform or yard car 4 to substantially the level of the 80 platform of the railway car or other vehicle 40, the inclination being sufficient to cause the bricks 45 to slip or slide off the movable platform or yard car moving on the rollers 43, onto the vehicle 40 which 85 should be drawn forward gradually so as to receive the bricks as they leave the movable platform. In this way the bricks will be delivered onto the car or other vehicle 40 without shock or jar and without danger of 90 breakage and in the order in which they were arranged on the movable platform or yard car so that no repiling or other rehandling is necessary.

When all of the bricks from a particular 95 kiln or storage pile have been disposed of by first piling them on the movable platform or yard car and transferring them to the railway cars or other vehicles in the manner above described, the hinged brackets 50 are 100 swung outward out of the way of the ends of the horizontal portions 6 and the corresponding parallel rail, and the screws 11, 20 and 21 are rotated by means of their hand wheels to lower the suspended frames till 105 their lower cross bars rest on the platform of the railway car or other vehicle 40, and are then further rotated to raise the cross bars 13 and 24 and with them the supporting uprights, until the bases of these uprights 110 are clear of the ground. The railway car or other vehicle may then be moved, carrying with it the complete loading device, to such other place near a second kiln or pile of 115 bricks as may be desired to load on cars or other vehicles for transportation. The inclined track will, of course, need to be separately transported unless a separate inclined track is used in connection with the second kiln or pile of bricks. When the 120 loading device is in its new position, all that is necessary is to rotate the screws 11, 20 and 21 until the bases of the uprights rest on the ground and then by further rotating the screws, lift the suspended frames until 125 the rail 6 and the parallel rail are in line with the rails of the inclined track, swing the brackets 50 into position to support the ends of these rails and the device is again ready for operation.

Having thus described my invention what I claim is:

1. In a loading device the combination of rails adapted to carry a movable platform each comprising two portions jointed together, a suspended frame supporting the forward ends of the rails, a second suspended frame supporting the rails at the joints between the portions thereof, the suspended frames being adapted to permit the movable platform to pass through them, and means for raising and lowering the first suspended frame.

2. In a loading device the combination of rails adapted to carry a movable platform each comprising two portions jointed together, a suspended frame supporting the forward ends of the rails, a second suspended frame supporting the rails at the joints between the portions thereof, the suspended frames being adapted to permit the movable platform to pass through them, means for supporting the suspended frames, and means for raising and lowering the suspended frames independently.

3. In a loading device the combination of rails adapted to carry a movable platform each comprising two portions jointed together, a suspended frame supporting the forward ends of the rails, a second suspended frame supporting the rails at the joints between the portions thereof, the suspended frames being adapted to permit the movable platform to pass through them, means for supporting the suspended frames, means for raising and lowering the first suspended frame, a track having the forward ends of its rails supported at an elevation in line with the rear ends of the rails carried by the suspended frames, and means carried by the track support for supporting the rear ends of said rails carried by the suspended frames.

4. In a loading device the combination of rails adapted to carry a movable platform each comprising two portions jointed together, a suspended frame supporting the forward ends of the rails, a second suspended frame supporting the rails at the joints between the portions thereof, the suspended frames being adapted to permit the movable platform to pass through them, means for supporting the suspended frames, and means

for raising and lowering the suspended frames independently, a track leading to the rear ends of the rails carried by the suspended frames, and means for supporting the rear ends of said rails.

5. In a loading device the combination of rails adapted to carry a movable platform each comprising two portions jointed together, a suspended frame supporting the forward ends of the rails, a second suspended frame supporting the rails at the joints between the portions thereof, the suspended frames being adapted to permit the movable platform to pass through them, a supporting frame for supporting the suspended frames comprising uprights having bases adapted to rest on the ground, a vehicle adapted to be run under the suspended frames, and means for raising and lowering the suspended frames adapted to lower the suspended frames onto the vehicle and to raise the supporting frame so that its bases will be free from the ground and the complete structure will be supported by the vehicle.

6. In a loading device the combination of rails adapted to carry a movable platform each comprising two portions jointed together, a suspended frame supporting the forward ends of the rails, a second suspended frame supporting the rails at the joints between the portions thereof, the suspended frames being adapted to permit the movable platform to pass through them, a supporting frame for supporting the suspended frames comprising uprights having bases adapted to rest on the ground, a vehicle adapted to be run under the suspended frames, means for raising and lowering the suspended frames adapted to lower the suspended frames onto the vehicle and to raise the supporting frame so that its bases will be free from the ground and the complete structure will be supported by the vehicle, a track leading to the rear ends of the rails carried by the suspended frames, and means for supporting the rear ends of said rails.

In testimony whereof I affix my signature this 11 day of July 1919.
